INVENTOR:

INVENTOR
August G. Johnson
By Kay Ethel Powell

UNITED STATES PATENT OFFICE.

AUGUST G. JOHNSON, OF MONESSEN, PENNSYLVANIA, ASSIGNOR TO PITTSBURGH STEEL COMPANY, OF PITTSBURGH, PENNSYLVANIA, A CORPORATION OF PENNSYLVANIA.

WIRE-FENCE MACHINE.

1,390,293.

Specification of Letters Patent. Patented Sept. 13, 1921.

Application filed October 24, 1918. Serial No. 259,572.

To all whom it may concern:

Be it known that I, AUGUST G. JOHNSON, a citizen of the United States, and resident of Monessen, in the county of Westmoreland and State of Pennsylvania, have invented a new and useful Improvement in Wire-Fence Machines; and I do hereby declare the following to be a full, clear, and exact description thereof.

10 My invention relates to mechanism for the manufacture of fabricated wire-fences of the design set forth and described in an application filed by me of even date herewith, Serial No. 259,590, said fence consisting of strand-wires and stay-wires, the stay-wires being arched at their upper ends and overlapping the adjoining wires, and said stay-wires alternately extending to the full height of the fence and to less than the full 20 height.

The object of my invention is to provide simple and efficient mechanism for fabricating the above described fence, and to these ends the invention consists, generally stated, 25 in means for feeding the stay-wires across the strand-wires, the stay-wires being fed alternately to the full height of the fence and to a lesser height, and means for arching said stay-wires so as to overlap the 30 adjoining wires.

In the accompanying drawings, Figure 1 is a face view showing the fence in process fabrication, the view being more or less diagrammatic; Fig. 2 is a section on the line 35 2—2, looking in the direction of the arrows; Figs. 3, 4 and 5 are enlarged details of the mechanism for arching the stay wires; Figs. 6 and 7 are views showing the ratchet and pawl mechanism for giving the long and 40 short feed to the stay wires; Fig. 8 is a sectional view of the gear and feed rolls for the stay wire and Fig. 9 is a fragmentary vertical sectional view showing somewhat diagrammatically the means by which the 45 welding members are reciprocated toward and from the work.

In the drawings, the numeral 2 designates a suitable frame in which is mounted the shaft 3, to which is keyed the arm 4. This 50 arm 4 carries the pawl 5, which is adapted to engage the ratchet 6 loosely mounted on the shaft 3. Connected to the ratchet 6, so as to rotate therewith, is the gear wheel 7. A trip is provided for the pawl 5, said trip

consisting of the roller 8 mounted on the 55 bracket 9 carried by the frame 2.

The ratchet 6 is provided with two sets of teeth 10, 10^a and 11, 11^a, so arranged, as will be more fully hereinafter described, that the pawl engaging said teeth alternately will 60 act to feed the stay wires alternately longer and shorter distances to give the construction of fence, as set forth in the above referred to application.

The gear wheel 7 meshes with the idler 65 12, said idler meshing with the gear-wheel 13 connected to the gear wheel 14, which meshes with the pinion 15. Secured to the gear wheel 14 and the pinion 15 are the feed-rolls 16 and 17 respectively. 70

The stay-wire 18 is fed by the rollers 16 and 17, said stay-wire passing through suitable guides 20 in front of and back of said feed rolls.

A shaft 21 is mounted in the frame 2. 75 Mounted loosely on said shaft is the eccentric 22 with the pitman 23 connected by the pin 24 to the arm 25. The arm 25 is pivotally mounted in the swiveled clevis 26 so that said arm has a vertical movement and 80 also a horizontal movement.

The arm 25 has at its inner end the finger 27 which engages the cam slot 28 in the bracket 29 secured to the frame.

The forward end of the arm 25 carries the 85 bending pin 30 which is adapted to engage the end of the stay wire and bend said stay-wire over the forming die 31, which is arched to give the proper curve to the upper end of the stay-wire, as clearly indicated in 90 Figs. 4 and 5. The forming dies 31 are carried by the bar 31^a, which is arranged to be moved to and fro at proper intervals, to engage and hold each stay-wire during the bending operation and during the welding 95 operation which takes place at the same time. Associated with the forming dies 31 are electric contact members, one of which is shown at 31^b on Fig. 2. The bar 31^a also carries other welding contact members 31^b, 100 one for each intersection between the strand-wires and the stay-wires. The purpose of these contact members is to weld the overlapping portions of the stay-wires and also the intersections between the strand-wires 105 and the stay-wires. To this end, these contact members are combined with an electrical welding circuit and control mechanism

which may be of the kind well known in this art. Each of the movable contact members 31^b carried by the bar 31^a coöperates with a stationary contact member 31^c on the opposite side of the fence and the overlapping and intersecting portions of the stay-wires are welded, while the next succeeding wire is being arched, by being clamped between the contact members 31^b and 31^c. Electric welding current may be supplied, as shown diagrammatically on Fig. 9, through lead wires 40 and 41 connected across any suitable source of power.

The bar 31^a carrying the contact members 31^b is reciprocated toward and from the work by any convenient mechanism, for example by means of the connections shown in Figs. 1 and 9. As shown in these figures, the shaft 21 carries two spaced cams 44 each of which has a circularly curved section 45 of small radius and a circularly curved section 46 of larger radius and which bears against a roller 47 carried at the end of a horizontal reciprocating rod 48, the outer end of which is pivotally connected at 49 to a lever 50. The upper end of the lever 50 is pivoted at 51 to a stationary bracket 52 and at its upper end is pivotally attached at 53 to the bar 31^a.
30 A suitable switch may be provided, as is usual in this art, for controlling the welding current at the time when the contact members 31^b are in engagement with the work. So far as the present invention is concerned, this switch may be omitted and the contact made and broken by the engagement between the contact members and the work. The wire feeding, welding and bending mechanism may be driven in proper time relation by any suitable power connections. As shown on Fig. 1 the bending and welding mechanisms are both operated directly from the shaft 21 and the shaft 3 which actuates the intermittent feed device may be driven from the shaft 21 through miter gears one of which is secured to the shaft 21 and the other to the shaft 3.

Mounted on the shaft 21 and keyed thereto is the arm 32 carrying the pawl 33. A ratchet 34 is carried by a sleeve 34^a that is loosely mounted on the shaft 21 and connected to the eccentric 22, said ratchet having the teeth 35. A trip roller 36 is mounted on the support 37 in position to trip the pawl, 55 as will more fully hereinafter appear.

Mounted on the shaft 21 to rotate continuously with this shaft is the eccentric 38 connected by the pitman 39 to an arm 40 similar to the arm 25, and said arm is mounted in a manner identical with the arm 25 and likewise carries similar bending mechanism for bending the long stay-wires.

In the operation of the machine, the strand-wires 41 are fed in a direction at right angles to the stay-wires, and as my inven-

tion does not relate to the feeding of these strand-wires, it has not been deemed necessary to illustrate this mechanism, as any well known form of mechanism may be used for this purpose. To form the fence covered by the above referred to application, it is necessary to change the distance of the feed of the alternate stay-wires, and to effect this result is the purpose of the pawl and ratchet device mounted on the shaft 3. As shown in Fig. 1, the pawl 5 has been tripped by the roll 8 and is about to disengage itself from said roll. It will be apparent upon its disengagement it will travel along the delay face of the ratchet until it comes into engagement with the tooth 11^a, as indicated in Fig. 6. The engagement of the pawl with the ratchet will rotate the gear wheel 7, and through it the intermediate gearing which drives the feed rolls 16 and 17, so that while said pawl is in engagement with the tooth 11^a of the ratchet, the stay-wire will be fed forward, and this will continue until, as shown in Fig. 6, the pawl reaches the trip-roll 8. In Fig. 6 I have indicated by the line α — α the amount of rotation imparted to the gear wheel 7. This will be sufficient to feed the stay-wire a full length, and upon the disengagement of the pawl from the ratchet the cutting of the stay-wire takes place. It has not been deemed necessary to illustrate this cutting mechanism, as any suitable cutter may be employed for this purpose. The end of the stay-wire is then bent by the action of the bending mechanism operated by the eccentric 38, which operates continuously.

After the pawl 5 has been thrown out of engagement with the tooth 11^a by the trip-roll 8, the pawl travels over the ratchet and the feed mechanism remains at a standstill until the ratchet engages the tooth 10^a, whereupon the feed mechanism is again operated, but for a shorter length of time, due to the fact that by the time the ratchet has rotated from γ to γ , as shown in Fig. 7, the trip-roll 8 will trip the pawl and stop the feed mechanism. In this way a short stay is formed, and when the stay has been cut the eccentric 22 is timed to operate by the pawl 33 engaging one of the teeth 35 of the ratchet 34, so that the arm 25 is operated to bend the end of the short stay-wire during the travel of the pawl to the next tooth. The pin 30 on said arm moves in a straight line for a certain distance and then, as indicated in Fig. 5, moves inwardly to give the curve to the wire. This is all accomplished by the action of the cam slot 28, the pin 24 being free to travel through the opening in the pitman 23. The bending mechanism for the short stays or wires operates intermittently, and this intermittent operation is effected by the pawl and ratchet 33 and 34, the pawl being tripped by the trip-roll 36, and only

being brought into operation when said pawl comes into engagement with one of the teeth 35.

It will be apparent that two sets of teeth 5 will be required on the ratchet 6, for as indicated in Fig. 1, the pawl has just been disengaged from one of the short stay teeth 10^a, and during the pawl's travel from that tooth to the tooth 11^a of the long stay-wire, 10 the bending of the short stay will be taking place. The teeth 11 and 11^a are therefore arranged at opposite sides of the ratchet, as are the teeth 10 and 10^a.

What I claim is:—

15 1. In a wire fence machine the combination with a suitable frame, of means for feeding the stay-wires transversely of the strand-wires, said stay-wires being fed the full height of said fence and to a distance 20 less than the full height, alternately, means for arching the upper end of each of said stay-wires toward an adjacent stay-wire, and means for securing said stay-wires to said strand-wires.

25 2. In a wire fence machine the combination with a suitable frame, of means for feeding the stay-wires transversely of the strand-wires, the stay-wires being fed to the full height of said fence and to a distance 30 less than said full height, alternately, means for arching the upper end of each of said stay-wires, means for securing said stay-wires to said strand-wires, and means for uniting the overlapping arched portions of 35 said stay-wires.

3. In a wire fence machine the combination with a suitable frame, of each of feed-rolls for the stay-wires, means for operating said feed-rolls whereby the stay-wires are 40 fed by the same feed rolls to the full height of said fence and to a distance less than the full height of said fence, alternately, and means for securing said stay-wires to the strand-wires.

45 4. In a wire fence machine the combination with a suitable frame, of a shaft, means for driving same, a pawl carried by said shaft, a ratchet loosely mounted on said shaft having two sets of oppositely arranged 50 teeth, tripping mechanism in the path of said pawl, feed-rolls for feeding the stay-wires, connections between said ratchet and said feed-rolls whereby said feed rolls are given different degrees of rotation alternately to feed said stay-wires to the full height of said fence and to a distance less than said full height, alternately, and means for securing said stay-wires to said strand-wires.

55 5. In a wire fence machine the combination with a suitable frame, of means for

feeding the stay-wires transversely of the strand-wires, a forming die for curving the upper ends of said stay-wires, a vertically and horizontally movable arm, a bending 65 pin carried by said arm, and means for moving said arm whereby said arm moves said pin in a straight line and then in a curved line for bending said wire around said forming die.

70 6. In a wire fence machine the combination with a suitable frame, of means for feeding the stay-wire transversely of the strand-wires, a forming die for curving the upper ends of said stay-wires, an arm 75 mounted to move vertically and horizontally, a bending pin carried by said arm, a shaft, an eccentric on said shaft, a pitman, a pin connecting said pitman with said arm and having a sliding connection therewith, a finger on the inner end of said arm, and a stationary member having a cam-slot engaged by said finger.

75 7. In a wire fence machine, the combination with a suitable frame of a pair of feed-rolls for feeding stay-wires, and means for imparting alternately different degrees of rotation to the said feed rolls, whereby the stay-wires are fed to the full height of said fence and to a distance less than the full 80 height of said fence, alternately, and means for securing said stay-wires to the strand wires of the fence.

8. In a wire fence machine, the combination with a suitable frame, of a pair of feed-rolls for feeding stay-wires, and means for imparting alternately different degrees of rotation to the said feed rolls comprising a driven shaft, a ratchet loosely mounted thereon and having a plurality of pairs of 95 100 diametrically opposed teeth, a pawl carried by said shaft and adapted to coöperate with the said ratchet, means for tripping the said pawl during each revolution of the said pawl, and driving connections between 105 said ratchet and said feed rolls.

9. In a wire fence machine the combination with a suitable frame, of means for feeding the stay-wires transversely of the strand-wires, a forming die for curving the 110 upper ends of said stay-wires to meet the next succeeding stay-wire, a movable bending member, and means for causing the said movable bending member to move parallel to the forming surface of the said die.

115 In testimony whereof, I, the said AUGUST G. JOHNSON, have hereunto set my hand.

AUGUST G. JOHNSON.
